Primary Examiner — Susan Bennett Hattan*Assistant Examiner* — Marie Fast Horse(74) *Attorney, Agent, or Firm* — Hickman Palermo
Becker Bingham LLP(57) **CLAIM**

An ornamental design for a data processing device, as shown and described.

DESCRIPTION

FIG. 1 is a perspective view of a data processing device according my new design;

FIG. 2 is a top view thereof;

FIG. 3 is a side view thereof, and of which the front view, back view, and other side view are the same; and,

FIG. 4 is a bottom view thereof.

Broken lines in the drawings depict portions of the data processing device that form no part of the claimed design.

1 Claim, 3 Drawing Sheets(56)
